EARTH MOVING EQUIPMENT

Gerald I. Clark, Mountain View, Calif., assignor to Woodridge Manufacturing Company, Sunnyvale, Calif., a corporation of Nevada.

Application October 23, 1939, Serial No. 300,729

8 Claims. (Cl. 37--126)

This invention relates generally to earth moving equipment of the type utilizing an earth cutting or scraping blade, together with a bowl or like structure for receiving and carrying a load to a point of discharge. More particularly, the invention relates to earth moving equipment making use of both a main bowl structure and an auxiliary bowl or front apron, with provision for raising the front apron and for adjusting the cutting blade during a loading operation, for closing the front apron to facilitate carrying the load, and for discharging the load from both the front apron and the main bowl.

An object of the present invention is to provide improved equipment of the above character, particularly with respect to affording more flexibility and latitude with respect to manipulation and control. In this connection the invention is characterized by a type of control whereby raising and lowering of the cutting blade and movements of the front apron can be better coordinated by an operator.

A further object of the invention is to provide earth moving equipment of the above character in which it is possible to discharge the main bowl independently of manipulation of the front apron.

A further object of the invention is to provide earth moving equipment capable of both slow and rapid load discharging operations.

Another object of the invention is to provide earth moving equipment capable of compressing the material being loaded during a loading operation, whereby the total load may be increased.

Additional objects and features of the invention will appear from the following description in which the preferred embodiments have been set forth in detail in conjunction with the accompanying drawings.

Referring to the drawings—

Figure 1 is a side elevational view showing earth moving apparatus incorporating the present invention;

Figure 2 is a plan view of the equipment shown in Figure 1;

Figure 3 is a side elevational view, in cross section, illustrating a suitable type of power take-off for a tractor, for use in conjunction with the equipment;

Figure 4 is a plan view of the power take-off shown in Figure 3;

Figure 5 is a detail, in end elevation, showing clutch and brake control elements for one of the drums;

Figure 6 is an end elevational view showing two

drums of the power take-off, mounted in alignment and controlled from a single lever;

Figure 7 is a side elevational view of earth moving equipment, incorporating the invention, but being a different embodiment from that shown in Figure 1; and

Figure 8 is a view similar to Figure 7, but showing a further embodiment of the invention.

Figure 9 is an enlarged cross sectional detail 10 showing a modified construction for the power take-off.

Referring first to Figures 1 and 2, the equipment illustrated is of the type including a wheeled frame A carrying the main and auxiliary bowls B and C, and adapted to be drawn by a tractor D. The tractor has a so-called power take-off E, by means of which certain parts of the equipment are operated.

While the details of the bowl structure may 20 vary in practice, as illustrated it consists of reinforced side walls 11 having rear extensions 12 which connect with an axle for the rear supporting wheels 13. The frame A is in the form of a yoke with the extensions of the yoke having 25 pivotal connection 14 with the sides 11 of the bowl. Near the forward end of the main bowl there is a cross connecting beam or strut 16 serving as a mounting for the earth cutting or scraping blade 17.

As a part of the main bowl structure, and for carrying out a discharge operation, the bottom and rear walls of the bowl are formed as a movable member 18, which has a hinged connection 19 with the cross strut 16. It will be evident that 35 when the hinged member 18 is swung upwardly and forwardly, it effectively causes the discharge of a load from the main bowl structure.

The auxiliary bowl structure C, or front apron, includes the side walls 21 and bottom load supporting wall 22. For supporting this auxiliary bowl to enable it to move in a general vertical direction with respect to the cutting blade 17, it is rigidly attached to the side arms 23, which in turn have pivotal connections 24 to the sides 11 of the main bowl structure.

The main frame A has a swivel connection 26 with the front axle 27, and this axle in turn forms a mounting for the front supporting wheels 28. This axle is also attached to the draft bar 29, which is adapted to be coupled to the tractor D.

While various types of motive means can be applied for raising and lowering the blade 17, for raising and lowering the front apron C, and for swinging upwardly and forwardly the hinged member 18 of the main bowl structure, in the

present preferred embodiment forces are applied to these parts by three cables 1, 2 and 3. Cable 1 is connected to the main bowl structure so that upon pulling or playing out this cable, the sides of the bowl and also the cutting blade 17 are raised or lowered. Cable 2 connects with the front apron or auxiliary bowl C. Cable 3 connects with the hinged member 18.

Cable 1 is guided by the sheaves 31 and 32 which are carried by a suitable mounting supported on the forward part of frame A. From sheave 32 the cable extends to the drum 33, to which the cable is anchored and about which it is wrapped. Drum 33 is carried by a vertical shaft 34 upon the frame A of the machine, and mounted upon this drum 33 there is a smaller drum 36. Cable 1a is anchored to and wrapped about the smaller drum 36, and is looped through the sheave blocks 37 and 38; and anchored at 39 to one of the sides 11 of the main bowl structure. The sheave blocks 37 and 38 connect with the cables 1b, and these cables in turn are guided by sheaves 41 and 42, and attached at 43 to the forward extensions 44 of the bowl sides 11. Each pair of sheaves 41 and 42 are mounted in suitable sheave enclosures or boxes 46, and these boxes are in turn secured to the main frame A. When cable 1 is pulled, drums 33 and 36 are rotated, and the winding up of cable 1a on drum 36 applies forces equally to blocks 37 and 38 to pull cables 1b and thus raise the forward portion of the main bowl structure and the cutting blade 17. Playing out cable 1 likewise results in a lowering of the cutting blade 11, with the cables being maintained taut because of the weight of the bowl structure.

Cable 2 is guided over the sheaves 41 and 48, which are likewise carried on the forward part of the frame A. From sheave 48, cable 2 is guided over the sheave 49, which is carried upon the main frame of the machine immediately above the drums 33 and 36. From sheave 49, the cable 2 is guided over the sheave 51 which is carried by a mounting 52. Mounting 52 is in turn secured to a cross beam 53, which extends between the sides 11 of the main bowl structure. From sheave 51, the cable 2 is looped under the sheave 56, and is then provided with an anchorage 57 to the mounting 52. Mounting 58 for sheave 56 is carried by the front apron or auxiliary bowl C. Pulling upon cable 2, therefore, swings apron C forwardly and upwardly while playing out of the cable permits the apron to drop back by gravity.

Cable 3 is guided by sheaves 59 and 60, likewise mounted upon the forward part of the machine frame. From sheave 60, the cable extends over a sheave 62 carried by mounting 52, and is looped over a sheave 63 and provided with an anchorage 64 upon the mounting 52. Sheave 63 is carried by mounting 66, which in turn is secured to the hinged member 18. Therefore pulling upon cable 3 swings the hinged member 18 upwardly and forwardly, while playing out of the cable permits this member to drop back to its normal position by gravity. Power take-off E is of the type provided with three separate winch drums 71, 72 and 73 (see Figure 3) about which the cables 1, 2 and 3, respectively are wrapped. Drums 71 and 72 are controlled by the lever 74, while the drum 73 is controlled by lever 76. These levers are in convenient position for use by an operator of the tractor. The mechanism associated with lever 76 is such that for one operating position of this lever, power is applied

to drum 73 to wind up its associated cable 3, while for another operating position the brake for this drum is released and the drum is permitted to unwind to play out cable 3. The mechanism associated with lever 74 is such that this lever has several operating positions. In one operating position, power is applied to rotate winch drum 71, while for a second operating position the brake for this drum is released, and the drum permitted to unwind to play out cable 1. For another operating position of lever 74, power is applied to rotate the upper drum 72, to wind up cable 2, while for a fourth operating position of lever 74, the brake for drum 72 is released and this drum is permitted to unwind to play out cable 2. In addition to the four operating positions just mentioned for lever 74, this lever has one, and preferably two, additional operating positions, in one of which power is applied to rotate drum 71, while simultaneously the brake for drum 72 is released and this drum permitted to unwind. The other additional operating position serves conversely to apply power to rotate drum 72, while the brake for drum 71 is released, and this drum permitted to unwind. The last two operating positions permit certain operations to be carried out simultaneously to afford better manipulation as will be presently explained.

Various mechanisms can be utilized in the construction of the power take-off E, in order to afford the features described above. A desirable type of power take-off is shown in Figures 3 to 6, inclusive. Briefly, this power take-off includes a housing 78, upon which the drums 71, 72 and 73 are carried and which is adapted for attachment to a tractor. The housing carries a pair of vertical shafts 79 and 81, which are journaled by the roller bearing assemblies 82 and 83. The lower end of each shaft is keyed to a worm gear 84, and these gears are driven by the worm 86. This worm is in turn secured to a drive shaft which is driven by the tractor motor. Drum 71 is journaled upon shaft 79, as by means of roller bearing assemblies 87, and drum 72 is journaled upon shaft 79 above drum 71. A sleeve 88 is secured to drum 71 and extends upwardly within drum 72 for a purpose to be presently explained. The journal for drum 72 includes the roller bearing assemblies 89 and the assembly 91 between the sleeve 88 and shaft 79.

The mechanism whereby movement of lever 74 causes desired operation to drums 71 and 72 includes in this instance an arrangement of clutches and releasable brakes. Thus above drum 72 a clutch cone 92 is splined upon shaft 79. Below the cone 92 there is a cone 93 which is connected to the sleeve 88. Thus when cones 92 and 93 are in engagement, rotation of shaft 79 drives the sleeve 88 to rotate the lower drum 71. Sleeve 88 is therefore a torque tube for transmitting torque to the lower drum 71. Above the cone 92 there is another cone 94 which is carried by the cylindrical shell 96. This shell is mounted upon the upper side of the drum 72, whereby this drum is driven when cones 92 and 94 are in engagement.

Instead of having a fixed mounting for cone 94, it is desirable to provide for adjustment as shown in Fig. 9. In this instance the cone 94 is carried by an extension 94a, the upper end of which is threaded. Extension 94a fits within ring 95, which is clamped to shell 88. An internally threaded ring 100 is threaded upon the

upper end of extension 94a and is clamped to ring 85. Upon removing lock pin 109a, one can rotate cone 94 relative to ring 100 to adjust the cone in a vertical direction.

At the upper end of shaft 79 there is a sleeve 97 to which the shaft is journaled as by means of a bearing assembly 88. The outer periphery of sleeve 97 is threaded and is engaged by the nut 99. This nut 99 is shown connected to the cone 92 as by means of a bearing assembly 101, this assembly being such that it is capable of applying thrust in either direction. A bracket 102 is secured to the nut 99, and the lower end of lever 74 is secured to this bracket by pivot pin 103. This axis of the pivot pin is horizontal so that when the forward end of lever 74 is swung to the right or to the left, nut 99 is turned to cause cone 92 to engage either cone 93 to drive the lower drum 71, or cone 94 to drive the upper drum 72.

The lower drum 71 is provided with a brake drum 106, embraced by the brake band 107. The cylindrical shell 96 upon drum 72 also forms a brake drum, which is adapted to be engaged by the brake band 108. Extending alongside the drums 71 and 72 there is an upright 109 which has its lower end attached to the housing 78. The corresponding ends of each of the bands 107 and 108 are anchored to the upright 109 by means of the adjustable tie bolts 111. The other ends of the brake bands connect with links 112 and 113 (Fig. 6) which in turn pivotally connect with the ends of lever arms 114 and 115. Arms 114 are mounted upon a shaft 116 which extends vertically and which is journaled on the upright 109. Lever arms 115 are mounted upon a tubular shaft 118, which is journaled upon shaft 116.

In order to bias both shafts 116 and 118 in a clockwise direction, as viewed in Figure 4, compression springs 121 are provided (Figure 4) which react upon the arms 122 and 123, mounted respectively upon the shafts 116 and 118. The force of springs 121 in effect serves to tighten the brake bands about their respective drums, so that normally these drums are locked against rotation in a counter-clockwise direction as viewed in Figure 4. The upper ends of shafts 116 and 118 are connected to the lever arms 114 and 115, respectively. These lever arms extend into proximity with the lower portion of control lever 74 where this control lever is provided with a cam roller 126. Lever 124 has an angular portion 127 which is engaged by roller 126 when lever 74 is swung forwardly (and downwardly) from the position shown in Figure 4, whereby such movement of the control lever causes lever arm 127 to swing in a counterclockwise direction (as viewed in Figure 4) to turn the corresponding shaft 116 and thus release the lower brake band 107 for the drum 71. Lever arm 125 is provided with two angular portions 128 and 129 which extend at angles of approximately 45° with respect to the line of centers between roller 126 and shafts 116 and 118 (see Figure 4). Thus movement of roller 126 rearwardly (with respect to direction of travel and as viewed in Figure 4), or to the right, causes engagement between this roller and portions 128 and 129, to swing lever 125 counterclockwise as viewed in Figure 4, thus similarly turning tubular shaft 118 to release the brake band 108 for the upper drum 72.

To briefly summarize the various ways in which control lever 74 serves to control the driving and release of the drums 71 and 72, when the tractor operator grasps this lever and swings it horizon-

tally to the left (Figure 2), cones 92 and 93 are engaged so that worm 86 drives through gear 84, shaft 79, cones 92 and 93, and torque tube 88, to rotate the lower drum 71. Brake drum 107 releases automatically. When lever 74 is swung horizontally in an opposite direction from neutral position, nut 99 is turned to cause cones 92 and 94 to engage, whereby the drive is similarly established from worm 86 through shaft 79, to the upper drum 72. Starting again from neutral position, as the operator swings lever 74 upwardly, roller 126 swings rearwardly to engage the lever portion 129, whereby lever 125 is turned in a counterclockwise direction, as viewed in Figure 4, to release the upper brake band 108, and thereby permit rotation of the upper drum 72 to play out the cable wrapped upon the same. To permit unwinding movement of the lower drum 71, the operator forces lever 74 downwardly from neutral position, whereby roller 126 engages lever portion 127 to turn lever 124 counterclockwise, as viewed in Figure 4, thereby releasing the lower brake band 107. In addition to the operating positions just specified for lever 74, if this lever is both swung to the right and simultaneously swung upwardly, it will be evident that cam roller 126 not only engages lever portion 129, to release the upper brake band 108 and permit unwinding movement of the upper drum 72, but at the same time rotation of nut 99 moves the cone 92 into engagement with cone 93, to complete the drive to the lower drum 71. Thus the lower drum 71 is driven to wind up its cable, while the cable applied to the upper drum is simultaneously played out. It is also possible to move lever 74 from neutral position both downwardly and to the left, in which event lever portion 127 is engaged by roller 126 to swing lever arm 124 and thus release the lower brake band 107 of drum 71, and to rotate nut 99 whereby cone 92 is engaged with cone 94 to establish drive connection to the upper drum 72. Therefore, for this last operating position, the cable on drum 72 is wound up, while the cable applied to the lower drum 71 is played out.

With respect to additional elements associated with drum 73, this drum is journaled upon shaft 81, as by means of ball or roller bearing assembly 131 and 132. A clutch cone 133 is splined upon the shaft 81 above drum 73, and this cone is adapted to engage a cone 134 formed in the upper part of the drum. The upper part of the drum is also cylindrical to form a brake drum 136 which is engaged by the brake band 137. At the upper end of shaft 81 there is a sleeve 138, corresponding to sleeve 97 upon shaft 79. Sleeve 138 is journaled to the upper end of shaft 81, as by means of a ball or roller bearing assembly 139. The nut 141 is threaded upon sleeve 138, and is connected to the hub of clutch cone 133 as by means of a roller or ball bearing assembly 142. A rigid member 140 connects the two sleeves 97 and 138, and may be braced by attachment with upright 109. Thus rotation of nut 141 moves the clutch cone 133 between engaged and released positions. Operating lever 76 is attached to nut 141, as shown in Figure 5.

Brake band 137 is likewise arranged to be self releasing when power is applied to the drum 73, and one end of this band is shown attached to the vertical support 143, by the adjustable tie bolt 144. The other end of the brake band 137 is pivotally connected to the links 146, which in turn connect with the lever arms 147. Arms 147 are mounted upon the vertical rock shaft 148,

and this shaft is journaled in brackets mounted upon the supporting member 143. A compression spring 149, acting against a lever 151 mounted upon shaft 148 urges this shaft to rotate in a counterclockwise direction as viewed in Figure 4. An arm 152 is also mounted upon the upper end of shaft 148, and extends into a position to be engaged by the projecting cam portion 153 formed on nut 141. Thus when nut 141 is rotated in counterclockwise direction from the position shown in Figure 4, arm 152 is swung to the left and shaft 148 rotated to release the brake band 157.

It will be apparent from the above that lever 16 has two positions from an intermediate neutral position for operation of the clutching means. When swung horizontally from neutral position in one direction, power is applied to rotate drum 73, because of engagement of clutch cones 133 and 134. When swung in an opposite direction from neutral position, shaft 148 is rotated by engagement of cam portion 153 with arm 152, thereby releasing the brake band 137 and permitting unwinding movement of the drum.

Referring again to Figures 1 and 2, operation of the complete equipment can be explained as follows: It will be presumed that one starts with parts in the positions shown in these figures and that the machine is being traversed over a ground surface from which earth is to be removed. One possible procedure is to swing lever 14 to the left (operator's left) whereby the drive is established to the top drum 72, to elevate the front apron C. Lever 14 is then moved back to neutral position, and when it is desired to take a cut, the cutting blade is lowered by swinging lever 14 downwardly. This releases the drum 71, thereby permitting cable 1 to be played out. While taking a cut, the height of the cutting blade 17 may be adjusted as desired by moving lever 14 to the left to drive drum 71, or by moving it downwardly to release this drum. As an alternative to this procedure, the operator may initially move lever 14 both to the right and downwardly whereby drum 72 is driven to pull upon cable 2 and thus lift the front apron C to a suitable "loading" position, and whereby drum 71 is released to simultaneously play out cable 1 and thereby lower the cutting blade 17. The latter manipulation can frequently be used to advantage with a saving in time.

The load distributes itself within both the main bowl structure B and the auxiliary bowl C, and as the size of the load reaches permissible capacity, the operator swings lever 14 to his left to drive drum 71 and wind up cable 1 to elevate the cutting blade 17, and at the same time lever 14 can be swung upwardly to release the drum 72, and by playing out cable 2 permit the front apron C to drop down to closed position. It will be evident that although the raising of the blade can be continuous, and can be accompanied by simultaneous continuous closing movement of apron C, these movements are entirely under the control of the operator, and the blade 17 can be raised intermittently or in stages, and the front apron likewise lowered in stages, as the operator may desire. Also if desired the blade 17 may be raised continuously while the front apron is being lowered in stages, or conversely, the apron C can be lowered continuously while the blade is raised in stages. Raising of the blade 17 is continued until this blade together with the main bowl structure B and the front apron C are well

clear of the ground surface. This is what can be termed "carrying position" of the machine, and the load may now be conveyed to a point of discharge.

After initially taking a load short of maximum capacity, it is a simple matter for the operator to compact the load, after which the load may be increased. Thus after partially or entirely raising the blade 17 from the earth, and after 10 closing of the front apron C, the operator may operate lever 16 to drive the drum 73 and pull upon cable 3, thus causing the hinged member 18 to swing upwardly and forwardly to compact the load, and to re-distribute the center of gravity of the load in the direction of the front apron. After compacting the load in this manner, drum 73 is released to permit hinged member 18 to return to the normal position shown in Figure 1, after which the front apron C is again 20 raised and the blade 17 lowered to take on a further load.

Assuming now that the load has been carried to a point of discharge, where it is desired to spread the load over a substantial area, the 25 operator swings the lever 14 from neutral position to the right, whereby the upper drum 72 is driven to raise the front apron C and discharge a portion of the load over the cutting blade 17. Apart from or simultaneously with this operation, lever 14 can be swung downwardly to release drum 71, thus permitting the blade 17 to be adjusted to a position corresponding to the depth of the spread desired. At any time during upward movement of the front apron C, or 30 after the front apron has been moved to its upper limiting position, the operator moves lever 16 to drive drum 73, thus pulling upon cable 3 to swing the hinged member 18 upwardly and forwardly, whereby all the material in the main bowl structure is discharged. It will be evident that these discharging operations can be regulated and carried out in stages as desired, consistent with the depth of spread required and the type of material being handled. In instances 35 where it is desired to discharge a load rapidly, lever 16 is operated to swing hinged member 18 upwardly and forwardly, and simultaneously lever 14 is swung to the right to drive drum 72, thereby causing the apron C to simultaneously 40 swing upwardly. It will be evident that this procedure makes possible a rapid discharge of the load, a feature which is not possible in earth moving equipment of the type making use of a single cable connected to both the front apron 45 and the main bowl structure, and arranged to first elevate the front apron and to subsequently 50 discharge the main bowl structure.

After a discharge operation, the operator can quickly return the parts to the normal position 55 shown in Figure 1, for taking on another load. Thus lever 16 can be operated to permit the hinged bottom 18 to drop back to normal position, and simultaneously lever 14 can be swung upwardly and to the left to lower the cutting blade 17 and to place the apron C in proper position for a cut. If desired, suitable spring means can be employed to aid return of member 18 to normal position.

The embodiment of the invention illustrated 60 diagrammatically in Figure 7 makes use of a sliding gate within the bowl structure in place of a hinged bottom 18. The main bowl structure 161 has a fixed bottom 162 extending backwardly from the cutting blade 163. The gate 164 is mounted for sliding movement longitudinally of

the bowl structure, and is connected to the cable 3 from the drum 73. The front apron 166 is connected to arms 167, which in turn have pivotal connections 168 to the sides of the main bowl structure 161. This apron is connected to cable 2 which extends from the drum 72. A frame 169 is shown attached to the upper part of the bowl structure and serves as a mounting for the spring 171. A cable 172 leading from this spring is guided over sheaves 173 and attached to the sliding gate 164. This spring and cable connection serve the purpose of returning gate 164 to the initial position shown in Figure 7.

The forward frame 174 has rearwardly extending side members which are pivotally connected at points 176 with the sides of the main bowl structure. The main bowl structure is connected to a rear axle carrying the wheels 177, while the front frame 174 carries the wheels 178. Cable 1 is guided over the stationary sheave 179 carried by the forward part of frame 174, over sheaves 181 and 182, and anchored at 183 to the frame 174. Sheave 181 is carried by the frame 174, while sheave 182 is carried on one end of a beam 184, the other end of which has a pivotal connection 186 with the frame 169. Thus pulling upon cable 1 serves to raise the main bowl structure with respect to the ground surface.

Cable 2 is guided over sheaves 187 and 188, carried by frame 174, and also over the sheave 189 carried by frame 169, and finally attached at 191 to the front apron 166. Cable 3 engages sheaves 192 and 193, which are carried by frame 174, and also by sheaves 194 and 195, carried by the frame 169.

The embodiment of Figure 7 operates in substantially the same manner as the embodiment first described. In place of swinging the hinged member 18 upwardly and forwardly to discharge the main bowl structure, a pull upon cable 3 slides gate 164 forwardly to positively expel the load.

The embodiment of Figure 8 (shown diagrammatically) makes use of a main bowl structure which is tipped forwardly to discharge the load. Thus in this instance the machine includes a frame 197 carrying the forward and the rear wheels 198 and 199. The main bowl structure 201 has pivotal connections 202 attached to the side frame structures 203. These structures have 50 pivotal connections 204 with the side portions of the main frame 197. The front apron 205 is carried by arms 207, which in turn have pivotal connections 208 to members of the side frame structures 203.

Cable 1 is guided over sheaves 209 and 211 carried by the forward part of the frame 197, and also is passed over sheave 212 and carried by the bracket 213. From sheave 212 cable 1 is looped over sheave 214 and provided with a fixed anchorage 216 to bracket 213. Sheave 215 is carried by a mounting 217 which in turn is attached to a cross member connecting the frame structures 203. Upon pulling cable 1, the frame structures 203 are elevated about the pivotal connections 204 to raise the main bowl 201 and its forward cutting edge.

Cable 2 is guided over sheaves 218 and 219 which are carried by the forward portion of frame 197. Its upper end extends over sheave 221 carried by mounting 217. Its lower end has a connection 222 to the front apron 206.

Cable 3 is guided over sheaves 223 and 224 which are also carried by frame 197, and extends over sheave 226 for connection at 227 to the 78

upper rear corner of the main bowl structure 201. Thus a pull upon cable 3 causes the main bowl structure 201 to be tipped upwardly and forwardly about the pivotal connections 202.

The embodiment of Figure 8 operates in substantially the same manner as the embodiments previously described. However, in place of a bowl structure having stationary sides, the entire bowl structure tips forwardly to discharge that portion of the load which is within the main bowl structure and which is not discharged by elevating the front apron 202.

I claim:

1. In earth moving equipment, a wheeled frame, a main bowl structure carried by the frame, said bowl structure including a forward earth cutting blade mounted for adjustment in a vertical direction, an auxiliary load carrying bowl or apron in front of the main bowl and movable in a general vertical direction relative to the cutting blade, means under the control of a single operating lever for independently raising and lowering the cutting blade and raising and lowering the front apron, and means for discharging the main bowl structure.

2. In earth moving equipment, a wheeled frame, a main bowl structure carried by the frame, said bowl structure including a forward earth cutting blade mounted for adjustment in a vertical direction, an auxiliary load carrying bowl or apron in front of the main bowl and movable in a general vertical direction relative to the cutting blade, means under the control of a single operating lever for independently raising and lowering the cutting blade and raising and lowering the front apron, and means under the control of a separate lever for discharging the main bowl structure.

3. In earth moving apparatus, a wheeled frame, a main bowl structure carried by the frame, the bowl structure having an earth cutting blade near its forward end capable of adjustment in a vertical direction, an auxiliary earth carrying bowl or front apron disposed in front of the main bowl structure and movable in a general vertical direction with respect to the cutting blade, power means for raising and lowering the cutting blade, for raising and lowering the front apron, and for discharging the main bowl, and two control levers for said power means, one of said control levers when operated serving to effect discharge of the main bowl structure, the other of said control levers when operated serving to raise or lower the front apron or to raise or lower the cutting blade.

4. In earth moving apparatus, a wheeled frame, a main bowl structure carried by the frame, the bowl structure having a forward ground cutting blade capable of adjustment in a vertical direction, an auxiliary load carrying bowl or apron disposed in front of the main bowl structure and movable in a general vertical direction relative to the cutting blade, a pair of cables connected to the cutting blade and to the front apron, whereby by pulling or playing out one cable the level of the cutting blade is adjusted, and by pulling or playing out the other cable the front apron is raised or lowered, power means including a pair of winch drums upon which said cables are wound, and a single control lever for said winch drums whereby power can be applied to either winch drum for winding up its associated cable, or whereby either winch drum can be permitted to unwind to play out its associated cable.

5. In earth moving apparatus, a wheeled frame, a main bowl structure carried by the frame, the bowl structure including a forward earth cutting blade mounted for adjustment in a vertical direction, an auxiliary load carrying bowl or front apron disposed in front of the main bowl structure and capable of movement in a vertical direction relative to the cutting blade, a pair of cables having connections to the cutting blade and to the front apron whereby when one of the cables is pulled or played out the cutting blade is raised or lowered, and whereby when the second cable is pulled or played out the front apron is raised or lowered, power means including a pair of winch drums upon which said cables are wound, and means including a single control lever for controlling winding or unwinding rotation of said winch drums, whereby by operation of said lever either of said drums may be rotated to wind up its associated cable or permitted to rotate in an opposite direction to play out its associated cable, or whereby either drum may be rotated to wind up its associated cable while simultaneously the other drum is permitted to rotate to play out its associated cable.

6. In earth moving apparatus, a wheeled frame, a main bowl structure carried by the frame, the bowl structure having a forward cutting blade mounted for adjustment in a vertical direction, whereby the depth of a cut can be varied and whereby the cutting blade can be elevated to a carrying position or for leveling operations, an auxiliary load carrying bowl or apron disposed in front of the main bowl and mounted for movement in a vertical direction relative to the cutting blade, whereby the front bowl can be raised relative to the cutting edge during the taking on of a load, lowered to carry a portion of the load, and raised to discharge a portion of the load over the cutting blade, at least three operating cables, one cable being connected to the cutting blade and serving to raise and lower the cutting blade when the cable is pulled or played out, a second cable being connected to the front apron and serving to raise or lower the front apron when the cable is pulled or played out, and a third cable being connected to the main bowl structure whereby the main bowl structure is discharged when its associated cable is pulled, and power means for operating said cables, said power means including three winch drums upon which said cables are individually wound and two control levers for effecting operation of said three winch drums, one of said control levers serving to effect winding or unwinding movement of the winch drum connected to

the main bowl structure, whereby the main bowl structure may be discharged, and the other control lever having a plurality of operating positions whereby either of the drums connected to the second and third cables may be rotated to wind up its associated cable or permitted to unwind to play out its associated cable.

7. In earth moving equipment, a wheeled frame, a main load carrying bowl structure carried by the frame, the bowl structure having a forward ground cutting blade capable of adjustment in a vertical direction and also including a member movable for the purpose of discharging earth in the main bowl structure over the cutting edge, an auxiliary load carrying bowl or apron disposed in front of the main bowl structure and movable in a vertical direction relative to the cutting blade, power means for effecting either raising and lowering of the cutting blade or raising and lowering of the front apron independently of the cutting blade, a single operating lever for controlling said last named power means to cause the same to either raise or lower the cutting blade or to raise or lower the front apron independently of the cutting blade, and additional power means for effecting operation of said movable member.

8. In earth moving equipment, a wheeled frame, a main load carrying bowl structure carried by the frame, the bowl structure having a forward ground cutting blade capable of adjustment in a vertical direction and also including a member movable for the purpose of discharging earth in the main bowl structure over the cutting edge, an auxiliary load carrying bowl or apron disposed in front of the main bowl structure and movable in a vertical direction relative to the cutting blade, three operating cables each adapted to be pulled or played out, the first cable being connected to raise or lower the cutting blade, the second cable being connected to the front apron to raise or lower the same, and the third cable being connected to said movable member, three winch drums upon which said cables are individually wound, and means including a pair of control levers for selectively and independently controlling the operation of said winch drums, one of said control levers controlling winding or unwinding movement of the drum with which the third cable is associated, the second lever serving to control winding or unwinding movement of either one of the winch drums with which the first and second cables are associated.

GERALD I. CLARK.
